UNITED STATES PATENT OFFICE.

JESSE A. EMMERT, OF MONTROSE, MISSOURI, ASSIGNOR OF ONE-HALF TO
WILLIAM H. ANTHONY, OF SAME PLACE.

BOSOM-BOARD.

SPECIFICATION forming part of Letters Patent No. 322,703, dated July 21, 1885.

Application filed July 3, 1884. (No model.)

To all whom it may concern:

Be it known that I, JESSE A. EMMERT, a citizen of the United States, residing at Montrose, in the county of Henry and State of Missouri, have invented certain new and useful Improvements in Bosom-Boards; and I do declare the following to be a full, clear, and exact description of the invention, such as will enable others skilled in the art to which it app pertains to make and use the same, reference being had to the accompanying drawings, and to the letters and figures of reference marked thereon, which form a part of this specification.

15 My invention relates to the class of ironing-boards known as "bosom-boards," and has for its object a simple, inexpensive, and easily-manipulated construction, whereby the shirt can be readily stretched and securely held on the board, in order that the bosom may be properly polished, as is desirable.

It consists in the board provided in its edge with a continuous groove enlarged at the head and base of the board for the reception of the 25 springs of the fastening-bail, and the fastening-bail composed of two similar rods having their adjacent ends united by retracting-springs, and formed substantially as herein-after more fully described and claimed.

30 In the drawings, Figure 1 is a perspective view of the board alone. Fig. 2 is a plan view of the board and bail connected as in operation. Fig. 3 is a detail view of the bail. Fig. 4 is a detail view of one of the corners of the bail, all of which will be described.

The board A has its forward corners, *a*, rounded, in order that the bail may be more readily applied. Its rear corners are preferably made as shown, the base *a'* being cut at 40 right angles to the sides *a*. A groove, B, is formed in the edge of the board, and extends entirely around it, being enlarged in the head and base of the board to form mortises B', fitted to receive the retracting-springs of the bail. This bail C is formed of two rods, C² C², and the base and head springs D D', connecting the adjacent ends of rods C², as most clearly shown in Fig. 3. The rods C² C² are coiled at C', and have the long arms or rods C² and 45 50 the short arms C³ extended therefrom. The

coil C' is so formed that the arms C² C³ will rest normally at right angles to each other; but this coil enables the said arms to yield in either direction, as is desirable in adjusting the bail onto and off the board. These coils 55 have a further object—namely, to serve as handles for moving the board when the shirt is in place thereon. They also render easier the manipulation of the bail in the adjustment of same onto and off the board. 60

In practice, where it is desired to hold the board firmly from lateral movement, the coils C' may be caught over pins or studs mounted on the table or support, and the board be thus securely held.

65 The short arms C³ fit in the grooves in the base, and the base-spring D connects the ends of the two arms and rests in the mortises B' of the base, as will be understood from Fig. 2.

The forward ends of arms C² are curved 70 correspondingly to the parts *a* of the board, and are connected by coil-spring D', which rests in the head mortise B'. (Shown in Fig. 2.)

In operation the shirt is placed on the board 75 with the bosom fitting on or over the face of same. The rear arms, C³, of the bail are drawn slightly apart, expanding the spring D, and the forward end of the bail is adjusted over the head of the board and into the 80 groove therein. The base of the bail is now sprung over the base of the board and into the groove, and the shirt will be firmly held and cannot slip during operation. In removing the shirt it is only necessary to draw the 85 arms C³ slightly apart and spring same up over the base of the board, when the shirt may be taken thereoff.

The spring-loop C' may be made of one or more coils of the bail-rod. For the purposes 90 of a handle, it will be understood the wire may be simply looped at the corners and crossed and soldered, or otherwise secured, at the point of crossing; but I prefer the spring-loop for the reasons stated.

95 It will be seen that the base-spring D serves also to secure the shirt, as it holds the parts of same under it in the mortise B', and thus more firmly secures the shirt at the base of the bosom.

Having thus described my invention, what I claim, and desire to secure by Letters Patent, is—

The combination, with the board A, having 5 edge groove, B, of the fastening-bail consisting of rods C, formed with the spring-coils C' and arms C² C³, extended from said coil at right angles to each other, and the springs D

D', connecting the adjacent ends of rods C C, substantially as and for the purposes set forth. 10

In testimony whereof I affix my signature in presence of two witnesses.

JESSE A. EMMERT.
